(57) **ABSTRACT**

A friction blade trim retention system is disclosed. The friction blade trim retention system uses friction blades that are biased radially outward to engage the interior wall of a can housing to hold a trim assembly of a recessed light fixture therein. The system includes vertical translating components that include spring biased detents to toggle between an upper position and a lower position. The detent lower position allows the installer to install the friction blade inside the can in a first step. The installer in the second step pushes the trim assembly upward into the can to engage the upper detent, thus completing installation.

CROSS-REFERENCE TO RELATED APPLICATIONS

This application is a continuation of co-pending application Ser. No. 15/872,918, filed Jan. 16, 2018, which claims priority from provisional application No. 62/446,825, filed Jan. 16, 2017; app. No. 62/487,459 filed Apr. 19, 2017; and app. No. 62/500,435 filed May 2, 2017, the contents of all of which are hereby incorporated by reference.

FIELD OF THE INVENTION

The present invention relates to residential and commercial light fixtures. In particular, the present invention relates to hardware used in ceiling light fixtures or similar luminaires.

BACKGROUND OF THE INVENTION

Recessed light fixtures are commonplace in residential homes and commercial buildings. A recessed light fixture typically has a metal housing or can, an electrical junction box, and a conical-shaped recessed trim assembly to direct and reflect the lighting emitted by a bulb (or similar light source) that is held inside by a bulb holder or socket. The can and junction box are supported on a pan. The can and pan assembly are installed above the ceiling of a building or house so that the opening in the can and the trim are flush with the ceiling. The light fixture is thus recessed into the ceiling. The light source inside the trim assembly can be an incandescent or halogen bulb, a compact fluorescent tube (CFL), an LED or the like.

A decorative trim ring is often attached to the trim assembly of the light fixture facing the floor, exposed to the living space beneath the fixture. The trim ring provides a finished look for the light fixture.

The can, trim assembly, junction box and pan are suspended by a pair of hanger bars extending parallel and on opposite sides of the pan. One type of standard ceiling is supported by joists, and the recessed light fixture is mounted onto the joists via the hanger bars. When the joists are made of wood or concrete, for example, the hanger bars are usually mounted to the joists with nails, screws or other standard mounting means. The weight of the light fixture is thereby supported by the joists through the hanger bars.

Alternatively, the ceiling may be of the "drop-down" or suspended type. A drop-down ceiling is a secondary ceiling often formed to conceal piping, wiring, HVAC, and/or the floor above. The drop-down ceiling typically consists of a grid-work of metal channels in the shape of an upside-down "T" (i.e., T-bar grid), suspended on wires from an overhead structure. The channels snap together in a regularly spaced pattern, and the resulting cells are filled with lightweight "acoustic ceiling tiles" or "panels" dropped into the grid. Light fixtures may be installed into the grid as desired.

SUMMARY OF THE INVENTION

The present invention in a preferred embodiment is directed to a recessed lighting trim retention system for supporting a light fixture inside a can housing. There are preferably at least two friction blade trim attachments. Each trim attachment has a first stationary portion having a horizontally elongated shape with resilient spring arms at

opposite ends, wherein each spring arm terminates in a friction blade having an edge for engaging an interior of the can; and a second stationary portion including a channel formation joined to the first stationary portion, wherein the channel forms a vertical space between the first and second stationary portions. Each trim attachment further includes an elongated L-shaped mounting bracket translating vertically relative to the first stationary portion within the vertical space, wherein the mounting bracket includes a spring biased toggle means facing the vertical space. The elongated mounting bracket is attached to the light fixture. A complementary toggle means facing the spring biased toggle means is disposed on or integrated into the elongated mounting bracket or the second stationary portion. In operation, the spring biased toggle means and the complementary toggle means selectively engage each other to bias the elongated mounting bracket into either an up position or a down position of the light fixture relative to the can. The spring biased toggle means is preferably a bar spring having a peak or hump, and the complementary toggle means is preferably a protrusion, ridge, cross-member, or the like.

BRIEF DESCRIPTION OF THE DRAWINGS

FIG. 1 is a top plan view of a light fixture using a preferred embodiment friction blade trim retention system.

FIG. 2 is a side elevational view.

FIG. 3 is a cross-sectional view.

FIG. 4 is an exploded view.

FIG. 5 is a magnified detail view of the encircled area in FIG. 3.

FIG. 6 including FIGS. 6(a)-6(d) are, respectively, a top plan view, a left side view, a front elevational view, and a right side elevational view of the friction blade mechanism.

FIG. 7 is an exploded perspective view of the friction blade retention system.

FIG. 8 is a partial cutaway view of the friction blade retention system as implemented inside a can housing.

FIG. 9 including FIGS. 9(a) and 9(b) show the friction blade retention system in the high and low positions.

FIG. 10 is a top plan view of an alternative embodiment friction blade trim retention system.

FIG. 11 is a side elevational view of the embodiment in FIG. 10.

FIG. 12 is a cross-sectional view.

FIG. 13 is an exploded view.

FIG. 14 is a magnified view of the encircled area in FIG. 12.

FIG. 15 including FIG. 15(a)-(d), respectively, are a top plan view, a left side view, a front elevational view, and a right side view.

FIG. 16 is an exploded perspective view.

FIG. 17 shows the alternative embodiment friction blade trim retention system with light fixture installed inside a can.

FIGS. 18(a) and 18(b) show the friction blade retention system in a down position and an up position.

FIG. 19 is a top plan view of another alternative embodiment friction blade trim retention system as applied to a light fixture.

FIG. 20 is a side elevational view of the fixture from FIG. 19.

FIG. 21 is a cross-sectional view.

FIG. 22 is an exploded view.

FIG. 23 is a magnified view of the encircled area in FIG. 21.

FIG. 24 including FIGS. 24(a)-24(c), respectively, are a top, left side and front elevation view.

FIG. 25 is an exploded perspective view of the friction blade trim retention system.

FIGS. 26(a) and 26(b) are cross-sectional views of the friction blade trim retention system in a down position and an up position.

FIGS. 27-29 show, respectively, the various stages (i.e., down, middle and up positions) for installing the light fixture and friction blade trim retention system inside a can housing.

FIG. 30 in a top plan view shows still another alternative embodiment friction blade trim retention system applied to a trim assembly of a recessed light fixture.

FIG. 31 is a cross-sectional view of FIG. 30.

FIG. 32 is a side elevational view of the FIG. 30 embodiment.

FIG. 33 is a top perspective view of the FIG. 30 embodiment.

FIG. 34 is an enlarged detail view of the encircled area in FIG. 31.

FIG. 35 is another side elevational view.

FIG. 36 including FIGS. 36(a)-36(d), respectively, are a top, left side, front elevation, and right side views.

FIG. 37 is an exploded perspective view of that alternative embodiment.

FIG. 38 shows the alternative embodiment friction blade trim retention system with trim assembly installed inside a can housing.

FIGS. 39(a) and 39(b) show the down and up detent positions of the friction blade spring retention system.

FIG. 40 depicts how the friction blade trim attachment is assembled to the trim assembly.

FIG. 41 is a top plan view of another alternative embodiment friction blade trim retention system with trim assembly.

FIG. 42 is a cross-sectional view of the trim assembly taken along line A-A of FIG. 41.

FIG. 43 is a side elevational view of the trim assembly of FIG. 41 for a 5-inch can.

FIG. 44 is a perspective view of the friction blade trim retention system with trim assembly of FIG. 41.

FIG. 45 is an enlarged view of the friction blade mechanism.

FIG. 46 is a side elevational view of the trim assembly of FIG. 41 for a 6-inch can.

FIG. 47 is an exploded view of the friction blade mechanism.

FIG. 48 shows the friction blade trim retention system with trim assembly right before installation inside a can.

FIG. 49 shows the friction blade trim retention system with trim assembly during installation inside the can.

FIG. 50 shows the friction blade trim retention system with trim assembly after installation inside the can is complete.

FIGS. 51-52 show the down and up positions, respectively, of the friction blade.

FIGS. 53-54 show the down and up positions, respectively, of the friction blade mechanism.

FIG. 55 is an exploded view of the friction blade trim retention system with trim assembly.

FIG. 56 is a top plan view of yet another alternative embodiment friction blade trim retention system mounted to a disc light.

FIG. 57 is a side elevational view of an exemplary embodiment configured to fit a 5-inch can.

FIG. 58 is a cross-sectional view take along line A-A of FIG. 56.

FIG. 59 is an exploded view of the friction blade trim retention system mounted to a disc light from FIG. 56.

FIG. 60 is a side elevational view of an exemplary embodiment configured to fit a 6-inch can.

FIG. 61 is an enlarged view of the friction blade retention mechanism.

FIG. 62 is an exploded view of the friction blade retention mechanism.

FIGS. 63-65 show the three stages of the friction blade retention mechanism corresponding to the three stages depicted in FIGS. 66-68.

FIG. 66 shows the friction blade trim retention system mounted to a disc light just before installation inside a can.

FIG. 67 shows the friction blade trim retention system mounted to a disc light during installation inside the can.

FIG. 68 shows the friction blade trim retention system mounted to a disc light after installation inside the can is complete.

DETAILED DESCRIPTION OF THE PREFERRED EMBODIMENTS

The present invention is directed to a mounting system to be used primarily with a trim or trim assembly to be installed in a recessed light fixture. The present invention is novel, at least because it uses friction and compression forces to hold an assembly/trim in a recessed housing or "can," and a compression force again to keep the assembly/trim in contact with the finished ceiling or wall. In a preferred embodiment, this dual compression feature is self-contained on the trim assembly. The trim may also include a feature which limits how far the portion of the compression structure that interfaces with the fixture side wall can slide into the recessed housing or can. Pre-existing recessed housing structures can work with the present invention and the trim/assembly will hold tight against the ceiling or wall.

Conventional trim retention systems/mechanisms hold a trim or trim assembly within a recessed light fixture via torsion springs, friction blades, screws, etc. Friction blades are resilient arms that are compressed within a recessed fixture against the interior of the light fixture or can, and the friction between the fixture and the sharp edges of the blades prevent the trim/assembly from falling out of the fixture from gravity. These conventional mechanisms do not have a solid engagement snap, click, or detent lock, so the heavy trim may slip or fall out of the can over time due to ceiling vibrations and gravity.

Conventional torsion springs mounted on the trim or in the housing are compression springs which are installed in a manner that the springs stay in the compressed position within a bracket and slowly pop open within the bracket to pull the trim/assembly tight to the finished ceiling/wall and hold the trim/assembly within the fixture. This is a common and known method of mounting the trim for most housings with apertures greater than a 4-inch diameter. For housings with smaller apertures, friction blades alone have been used for most trims/assemblies.

Another conventional retention mechanism uses coiled tension springs to hold the trim assembly inside the can. The opposite ends of the tension springs are hooked to the can and the trim assembly, so the stretched springs bias the two structures together.

Some trim or trim assemblies are held by friction alone and others mate with an internal structure to allow compression between the spring and the internal structure along with compression to the side wall of the recessed fixture.

Those trim or trim assembly retention systems which use fasteners known in the art require the consumer to use tools for installation, which is an inconvenience for the consumer.

The fasteners are usually hidden in the upper portion of the trim assembly to improve aesthetics, but this limits access by the consumer during the installation process.

Single compression torsion springs lack the ability to pull the trim/assembly in tight or snug contact with the ceiling/wall. The compression of the springs happens in a lateral/horizontal fashion between the housing sidewall and the vertical section of the trim/assembly. There is no other action to help prevent a gap forming between the ceiling/wall and the trim/assembly. Most installations which feature this form of retention have some gap between the ceiling/wall. The gap is visible with the naked eye to the room's occupants, so it is highly undesirable.

Creating trim/assemblies to replace trim/assemblies in housings which have been installed creates challenges to using only the known retention mechanisms. Housings must be made to accept the dual compression springs or torsion springs. Those housings which have no means to accept these springs will be need a single compression, friction spring to squeeze against the housing sidewalls. This will hold the trim/assembly into the can or housing, but it will not pull it tight.

According to a preferred embodiment of the present invention depicted in FIGS. 1-9, the dual compression action is a function of the relationship between the trim and the recessed housing, designed to engage the friction spring in a manner that creates compression in two areas. The present invention structure is ideal since it preferably uses a dedicated trim and housing to work in unison.

From an economics perspective, the present invention helps suppliers who sell both the trim and housing complete the sale without the consumer using an alternate trim/assembly in the housing sold to mount in the ceiling. The dual compression also pulls the trim/assembly close to the ceiling/wall for a finished look with a tight fit.

The present invention in a preferred embodiment has a dual compression feature built into the trim assembly. The trim assembly has a spring that is installed in two motions. First, the assembly has a structure that allows the spring to be in compression and fixed in the housing for the initial portion of the installation process; and second, the trim assembly is pushed toward the housing aperture which activates the second compression or detent mode. The trim assembly is designed to compress the spring and pull the trim tight to the housing or can aperture.

FIGS. 1 and 2 are top and side elevational views, respectively, of a typical light fixture 10 having a circular or disk shape. Other shapes, such as a square, are contemplated. The light fixture 10 includes a trim assembly 12 having preferably a pan shape. The trim assembly interior contains a light source such as, in this embodiment, LEDs 14, facing downward as seen in the cross-sectional view of FIG. 3. Optionally covering the LEDs 14 is a dome-shaped diffuser or lens 16, which can be transparent, or translucent, and may have exterior surface texture and/or a color tint. Surrounding the LEDs 14 is an optional light reflector 22 having an annular shape with reflective coating covering its ID. The reflector 22 is intended to evenly redirect and reflect the LED emitted light through the dome lens 16 and minimize dark spots seen through the lens 16.

On the back side of the LEDs 14 and mounted to the trim assembly 12 is an LED driver 18 powering the LEDs 14, with an electrical quick-connect 20. The quick-connect 20 is known in the art and can be purchased off-the-shelf from various vendors. It connects the light fixture to a pre-existing quick-connect leading to the house or building's standard AC power supply (not shown).

FIG. 4 is an exploded view of the trim assembly 12 with the reflector 22 disassembled from the bottom and two friction blade trim retention attachments 24. There are preferably two friction blade trim retention attachments 24, mounted diametrically apart to the top of the trim assembly 12. The attachments 24 are intended to engage the interior curved wall of a standard recessed light fixture housing or can 26, as seen in partial cutaway view of FIG. 8.

FIGS. 6(a)-(d) are top, left side, front and right side 10 elevational views of a preferred embodiment friction blade trim retention attachment 24. FIG. 7 is an exploded view of 15 a preferred embodiment friction blade trim retention attachment 24. The attachment 24 includes an elongated, rectangular shaped friction blade 28 attached to a bracket 30 with two screws, rivets, spot welds, or the like, at a central 20 stationary portion 34. The blade 28 is made from preferably a steel flat spring or the like. Each blade 28 preferably has a sharp edge 44 to generate maximum friction and grip when pressing against the interior wall of the can 26. As seen in 25 FIG. 7, the blades 28 extend horizontally from the central stationary portion 34 via two opposed spring arms 36 that have spring bias. At the bottom of each blade 28 is an optional tab 38 located at the bottom. The spring arms 36 and blades 28 are the first spring component of the present invention.

As seen in FIG. 7, there is a vertical space 46 created in 30 between the central stationary portion 34 and the rear stationary portion 30(b), which preferably has a channel form to create the vertical space 46. That vertical space is 35 occupied by a V-spring 32 which itself is hooked to rear stationary portion 30(b). The V-spring 32 is a bar spring and has a resilient peak or hump 40, making the V-spring 32 the second spring component of the present embodiment. As such, the V-spring 32 is optionally entirely made from spring 40 steel and has a spring bias to retain its V-shape with the hump. FIGS. 6(a)-6(d) show the components of the attachment 24 assembled. The two spring components 28, 32, use bar springs, but coiled springs, torsion springs and their equivalents may be added or substituted for the bar spring.

FIG. 9 is a cross-sectional view showing the rear stationary portion 30(b) attached to the center stationary portion 34 creating a vertical space therebetween, with the V-spring 32 translating up and down within that vertical space. That is, the center stationary portion 34 is assembled to the rear 45 stationary portion 30(b) via the two machine screws so the two pieces move in unison, while the L-shaped mounting bracket 30(a) is attached to the trim assembly 12, so the two parts 30(a), 30(b) freely translate up and down relative to each other. When in use, the friction blade 28 of the center stationary portion 34 engages the interior wall of the can 26, while the mounting bracket 30(a), which is attached to the light fixture 10, can slidably translate the fixture 10 into the can 26 by moving from its position in FIG. 9(a) to FIG. 9(b).

As seen in FIG. 7, a rigid finger 42 or like raised 55 protrusion on the mounting bracket 30(a) extends into the vertical space, and selectively engages, depresses, and slides over the hump 40 of the V-spring 32 to create a toggle or detent action. This vertical toggle action is depicted in FIGS. 9(a) and 9(b). Thus, as the mounting bracket 30(a) is pushed 60 upwards by an installer (to install the trim assembly, FIG. 9(a)), the finger 42 partially deflects V-spring 32 as the finger moves upward toward the hump 40, and once the finger 42 deflects and slides over hump 40, the V-spring 32 resiliently returns to its original V-shape, forcing the finger 42 to slide down the opposite side of the hump 40, as seen in FIG. 9(b). The resilience in the V-spring 32 thus biases the 65 mounting bracket 30(a) and attached trim assembly 12

upward once the finger 42 slides past the peak in the hump 32 into its detent position. This upward bias essentially pulls the trim assembly 12 upward into the can 26, as perceived by the installer, ending with the installed state shown in FIG. 8.

FIG. 8 shows the attachment 24 with the trim assembly 12 installed inside the recessed light fixture can 26. The attachments 24 are used to retain the trim assembly 12/light fixture 10 to the can 26. In the first step of installation, spring arms 36 are seen deflected and pushed against their bias to conform to the ID of the can; the surfaces of the spring arms 36 thus frictionally engage the interior wall of the can 26 to hold the friction blade 28 and bracket stationary portion 30(b) in place, relative to the can 26, as seen in FIG. 9(a).

In the next step, the installer simply pushes up on the trim assembly 12 to overcome the resistance from the finger 42 engaging the hump 32, and once the finger 42 passes over the hump 32, the resilience in the V-spring restoring to its un-deflected state drives the finger 42 upward, and thus pulling the trim assembly 12 into the can 26. The stopper tabs 38 at the bottom of the friction blade 28 engage the underside lip of the can 26 and act as stops to prevent overtravel in the upward direction. The installation is now complete.

Disassembly of the trim assembly 12 from the can 26 only requires the installer to tug downward on the trim assembly 12 to overcome the spring bias of the finger 42 moving downward over the hump 40 of the V-spring 32, and to continue tugging to overcome the friction of the spring arms 36 against the ID wall of the can 26. Continued downward tugging fully detaches the trim assembly 12 from the can 26.

FIGS. 10-18 depict an alternative embodiment with a slightly different arrangement of the V-spring and bracket halves from the embodiment disclosed above. In this embodiment, the V-spring is attached to the sliding portion, and during the sliding motion, the V-spring hump selectively toggles into detent openings (corresponding to a high position and a low position) in the stationary portion of the bracket.

FIGS. 10-14 show the alternative embodiment friction blade trim attachment 50 installed on a trim assembly 12/light fixture 10 already described above. FIGS. 15(a)-(d) are top, left side, front and right side elevational views of the alternative embodiment friction blade trim retention attachment 50. FIG. 16 is an exploded view of the alternative embodiment friction blade trim attachment 50. The operation again uses a stationary component engaging the interior of the can by friction and spring bias and a sliding moving portion attached to the trim assembly to raise it into the can or lower it out of the can with positive engagement clicks or detents. Specifically, FIG. 16 shows the stationary portion halves 56(a) and 56(b), joined together by screws, rivets, tack welds, roll pins, or equivalent fastener. Sandwiched therebetween 56(a) and 56(b) is the movable mounting bracket 54. The mounting bracket 54 preferably has an "L" shape with an optional tab at the bottom for attachment to the trim assembly 12 as seen in FIG. 12. Joined to the mounting bracket 54 is the V-spring 52, and it translates up and down with the mounting bracket 54 relative to the stationary portion 56(a), 56(b).

Stationary portion 56(a) features spring arms 58 that have resilience and are made from spring steel or like material. At the distal ends of the spring arms 58 are friction blades 60 that scrape along the interior of the can 26 from installation to final rest position. The spring arms 58 have a radially outward spring bias when installed inside the can 26 to create a radially outward force that holds the weight of the

trim assembly 12 inside the can 26 against the force of gravity and any movement from ceiling vibrations. Furthermore, the friction blades 60 have a sharp edge that creates high frictional forces as they engage the interior wall of the can 26. The friction blades 60 further supplement holding the attachment assembly 50 immobile inside the can 26. The optional stopper tab 62 engages the bottom lip of the can opening so the installer knows that the attachment assembly 50 has been pushed as far up as possible inside the can 26, as seen in FIG. 17.

In this embodiment, the V-spring 52 is also made from a spring steel, preferably, but plastic spring parts, or torsion and coiled spring parts are contemplated. The V-spring 52 has a hump 64 that selectively engages a cross-member 66 formed into stationary portion 66, which looks like an "H." Thus, when the V-spring 52 moves up and down relative to the stationary portion 66, the hump 64 slides up and down over the cross-member 66, so the open areas above the below the cross-member 66 serve as detents for the hump 64 to toggle into the up and down positions. These up and down positions of the mounting bracket 54 relative to the stationary portion 56(a) are shown in the cross-sectional views of FIGS. 18(a) and 18(b). In those positions, the hump 64 is either snapped into the opening above (in FIG. 18(b)) or below (FIG. 18(a)) the cross-member 66. The hump 64 as mentioned above is resilient and with its sloped sides has a tendency to fall into a detent or toggle position above or below the cross-member 66.

FIGS. 17 shows the friction blade trim attachment 50 with light fixture 10/trim assembly 12 installed inside a can 26. The spring arms 58 have been deflected back, installed in the can, and released under spring bias to push the friction blades 60 against the can interior. The optional stopper tabs 62 abut the bottom lip of the can opening to ensure the attachment system 50 is installed fully up into the can. The mounting bracket 54 is shown partially moving toward its fully up position relative to the stationary portions 56(a), 56(b). This is why there is still a small gap between the bottom lip of the can opening and the trim assembly 12. Once the light fixture 10 and trim assembly 12 are pushed up further, and the hump 64 falls into the detent above the cross-member 66 (FIG. 18(b)), the gap will be closed so that the light fixture snaps tightly into position against the lip of the can opening.

FIGS. 19-24 show another alternative embodiment friction blade trim attachment 70 installed on a trim assembly 12/light fixture 10 already described above. FIGS. 24(a)-(c) are top, left side, and front elevational views of the alternative embodiment friction blade trim retention attachment 70. FIG. 25 is an exploded view of the alternative embodiment friction blade attachment 70. In this embodiment, the stationary portions 74(a) and 74(b) sandwich the moving, preferably L-shaped mounting bracket 72 therebetween. The stationary portion 74(a) includes a raised hump 80, and it slides over raised ridge 82. The movement of the ridge 82 relative to the hump 80 whether above it or below it creates the detent or toggle effect. This is illustrated in the cross-sectional view of FIG. 26(a) with the ridge 82 beneath the hump 80, and in FIG. 26(b) with the ridge 82 above the hump 80. These positions correspond to the mounting bracket 72 being in the lowered position of FIG. 26(a), and the raised position with the light fixture installed inside the can in FIG. 26(b). No V-spring is needed in this embodiment so the part is omitted.

FIGS. 27 shows the friction blade trim attachment 70 mounted to the light fixture 10/trim assembly 12 via the mounting bracket 72 right before installation to the can 26.

The spring arms 76 have not yet been deflected and are in the rest position. The mounting bracket 72 is in the lowered position relative to the stationary portions 74(a), 74(b). FIG. 28 shows the spring arms 76 being deflected back by the installer and inserted into the can 26, then released to bias the friction blades 78 against the interior wall of the can. The mounting bracket 72 is still in the down position. In FIG. 29, the installer has pushed the light fixture upward thus moving the mounting bracket 72 and sliding the hump 80 over the ridge 82 and snapping into position, as in FIG. 26(b). Installation is now complete, where the light fixture 10/trim assembly 12 fits snugly against the lip of the can. Removal only requires the installer reversing the above steps, i.e., tugging downward on the light fixture 10 to slide the ridge 82 downward over the hump 80. This pulls the trim assembly 12 from the interior of the can.

FIGS. 30-35 show still another alternative embodiment friction blade trim attachment 100 installed on a trim assembly 12 (or light fixture) already described above. FIGS. 36(a)-(d) are top, left side, front and right side elevational views of the alternative embodiment friction blade trim retention attachment 100. FIG. 37 is an exploded view of the alternative embodiment friction blade trim retention attachment 100. In this embodiment, the L-shaped mounting bracket 102 is again sandwiched in between the two halves of the stationary portion 104(a) and 104(b). A V-spring 106 is mounted to the mounting bracket 102 and the two components move in unison. As seen in the exploded view of FIG. 40, the mounting brackets 102 are assembled to a center bracket 114 which itself is disposed underneath the LED driver 18. The center bracket 114 preferably includes slots 118 to receive fasteners therein to attach to the L-shaped mounting brackets 102. The slots 118 allow the friction blade trim retention attachment 100 to mount to different diameter sized trim assemblies. Moreover, this arrangement with the center bracket 114 fully integrates the friction blade trim retention system with the trim assembly 12. This arrangement further accommodates larger diameter and greater height-dimensioned trim assemblies.

FIG. 37 shows the two halves of the stationary portions 104(a), 104(b) screwed together, but they may be riveted, spot welded, or assembled by other known techniques, or even formed as a single piece. For example, the parts 104(a), 104(b) may be molded from plastic and formed as a single piece. Stationary portion 104(a) includes spring arms 110 with friction blades 112 at their respective distal ends. Preferably, at least the spring arms contain spring bias and are preferably made for spring steel or the like. Stationary portion 104(b) has an "H" configuration, so that there is a cross-member 108. As the hump 116 of the V-spring 106 slides above or below the open areas of the cross-member 108, an upper detent and a lower detent are created, respectively.

FIG. 38 shows the alternative embodiment friction blade trim retention system with trim assembly installed inside a can housing. FIGS. 39(a) and 39(b) show the down and up detent positions of the friction blade spring retention system.

Specifically, FIG. 39(a) shows the cross-member 108 located above the hump 116, which corresponds to the lowered position of the hump 116 and mounting bracket 102, and the lowered position of the trim assembly 12. FIG. 39(b) shows the hump 116 and mounting bracket translated above the cross-member 108, which corresponds to the raised position of the mounting bracket 102 and installed position of the trim assembly 12 inside the can 26, shown in FIG. 38. FIG. 40 depicts how the friction blade trim attachment is assembled to the trim assembly.

FIGS. 41-55 depict yet another alternative embodiment of the friction blade trim system installed on a typical light fixture trim assembly 12 already described above. This alternative embodiment friction blade trim attachment 200 has generally the same construction as those described above, except as seen in FIG. 47, the single friction blade 212 in its un-deformed state includes a vertical section leading to an angled downward section leading to an upwardly hooked end at the scraper 222.

That is, the friction blade 212 is made at least partially of a spring steel in the form of a bar spring and preferably includes a single, resilient cantilevered arm 220 extending away toward an outside diameter of the trim 12 and terminating in a scraper 222. From a prior embodiment, e.g., FIG. 37, there may be at least two resilient, cantilevered arms/friction blades 112 extending in opposite directions. The scraper 222 has an optional flattened distal end including an optional V-notch to provide a radially-outward bias to push the scraper into the inside wall of the can 26. As seen in FIGS. 48-50, when installing the trim to the can, the friction blade 212 including the scraper 222 are compressed against spring bias of the blade 212 to fit within the inside diameter of the can 26. Once inside the can, the spring bias in the blade 212 urges the scraper 222 radially outward against the interior of the can 26. The scraper 212 preferably has a thin horizontal leading edge or distal tip that creates a high frictional coefficient as it engages the interior surface of the can 26. The leading edge or the entire scraper 212 may optionally be dipped or coated in a high friction material known in the art (not shown) to increase the friction between the scraper and the can. The high friction helps to further resist potential sagging of the trim away from the can due to gravity, environmental vibrations, spring creep, etc.

Back in FIG. 47, the friction blade 212 and the stationary portion 204 are assembled to each other somewhat loosely sandwiching a bracket having a generally "L" shape, i.e., L-bracket 202 therebetween. The L-bracket 202 has a vertical portion 226 such that the friction blade 212 and stationary portion 204 slide along it. This arrangement allows for relative translational motion between the friction blade 212 with its stationary portion 204 versus the L-bracket 202. Furthermore, the stationary portion 204 includes a rigid cross-member 204. A resilient member 206, generally a bar spring having a hump 216, is anchored to the L-bracket 202. The cross-member 204 in its translational motion up and down the vertical portion 226 of the L-bracket 202 is intended to deform the hump 216 of the resilient member 206 and slide over it while moving in either direction. When the cross-member 204 passes over the peak of the hump 216, the resilience in the hump 216 restores it to its undeformed condition, forcing the cross-member 204 to move "downhill." This creates the toggling or detent action.

Thus, all aspects of this embodiment are the same as described relative to the prior embodiments above. FIGS. 48-50 show the installation sequence, wherein FIG. 48 shows the friction blade trim retention system 200 with trim assembly 12 right before installation inside the can 26. FIG. 49 shows the friction blade trim retention system with trim assembly during installation inside the can. FIG. 50 shows the friction blade trim retention system with trim assembly after installation inside the can is complete.

FIGS. 51-52 show the down and up positions, respectively, of the friction blade 212 and stationary portion 204 relative to the L-bracket 202 and the hump 216, which hump enables the vertical translational motion and toggling action. FIGS. 53-54 show the same action in enlarged views inside

11

the can 26. FIG. 55 is an exploded view of two friction blade trim retention attachments 200 and how they are mounted via fasteners to the trim assembly 12 with a center bracket 214.

FIGS. 56-68 depict still another alternative embodiment friction blade trim retention system attachment 228 and its use with a trim assembly, here an LED disc light 12. FIG. 62 is an exploded view of this alternative embodiment. Each friction blade trim retention attachment 228 uses a torsion spring 232 in place of the bar springs of the prior embodiments. Thus, it is contemplated to use torsion springs in place of bar springs with the disclosed embodiments above. The torsion spring 232 has two resilient legs 234 with its coil attached to an L-bracket 202. As seen in FIG. 62, friction blade 212 has a single resilient cantilevered arm 220 terminating in a scraper 222. The friction blade 212 is assembled to cross-member 236 while loosely sandwiching the vertical portion 226 of the L-bracket 202 therebetween with sufficient space for relative translational or sliding movement.

In this embodiment, the legs 234 of the torsion spring 232 are normally biased apart. The distal ends of the legs 234 are pinched closer together under finger pressure against the torsion spring bias, then passed through a narrow slot 248, and released. This assembly step is performed at the factory. Once released, the resilience in the legs 234 tends to restore to their original un-pinched shape, spreading back towards open. This spreading bias of the legs 234 inside the slot 248 tends to hold the position of the torsion spring 232 (which engages the can 26) relative to the L-bracket 202 (which is attached to the disc light 12), thus holding the position of the disc light 12 relative to the can 26.

This sequence of events is depicted in FIGS. 66-68. Specifically, FIG. 66 shows the friction blade trim retention attachments 228 mounted to a disc light 12 just before installation inside the can 26. In this view, the legs 234 have already been pinched closer together and inserted into the slot 248. FIG. 67 shows the friction blade 212 being compressed by the inside wall of the can 26, with the trim retention attachments 200 mounted to the disc light 12 partially inserted into the can 26. FIG. 68 shows the resilient legs 234 moved farther through the slot 248, wherein the spreading bias of the legs 234 holds their position within the slot 248. Thus, the disc light 12 is held firmly in place relative to the can 26. Gravity pulling downward on the disc light 12 is resisted by the spreading bias of the legs 234 against the slot 248, thus preventing any downward sagging of the disc light away from the bottom of the can 26. There is also great friction between the angled legs 234 versus the inner edge of the slot 248 that minimizes the legs moving downward back out of the slot due to gravity, vibrations, or spring creep. Installation inside the can 26 is now complete. Separating the disc light 12 from the can 26 only requires the user tugging downward on the disc light to overcome the spring bias of the spreading legs 234 against the slot 248.

This action is depicted in side elevational views of the friction blade trim retention system 228 in FIGS. 63-65. FIG. 65 corresponds to the pre-installation state in FIG. 66; FIG. 63 corresponds to the during installation state of FIG. 67; and FIG. 64 corresponds to installation completed state of FIG. 68.

The preferred embodiments replace conventional torsion springs because they will work with housings with or without dedicated features to interface with the torsion springs. Further, the holding power to retain the trim assembly snugly to the can is much improved by using friction and radial spring bias. This holding power resists gravity's pull

12

over time and ceiling vibrations that might eventually overcome the slowly weakening spring stiffness in a conventional torsion spring.

While particular forms of the invention have been illustrated and described, it will be apparent that various modifications can be made without departing from the spirit and scope of the invention. It is contemplated that components from one embodiment may be combined with components from another embodiment.

What is claimed is:

1. A recessed lighting trim retention attachment system for supporting a light fixture trim inside a can, the trim retention attachment comprising:

an L-shaped bracket including a vertical portion;
a friction blade including a resilient cantilevered arm terminating in a scraper at a distal end;
a resilient member disposed on the L-bracket;
a cross-member assembled to the friction blade such that the L-shaped bracket is slidably held therebetween along the vertical portion, and the resilient member slidably engages the cross-member such that the cross-member is biased in a direction along the vertical portion of the L-bracket; and
wherein the L-bracket is affixed to the light fixture trim, and the scraper frictionally engages the inside of the can to hold the light fixture trim inside the can.

2. The recessed lighting trim retention attachment system of claim 1, wherein the scraper includes a V-notch and terminates in a flat distal end.

3. The recessed lighting trim retention attachment system of claim 1, wherein the resilient member includes a flat bar spring.

4. The recessed lighting trim retention attachment system of claim 1, wherein the resilient member includes a coiled torsion spring with two legs biased apart.

5. The recessed lighting trim retention attachment system of claim 1, wherein the friction blade includes a spring steel.

6. The recessed lighting trim retention attachment system of claim 3, wherein the flat bar spring includes a hump, and the cross-member slidably engages the hump.

7. The recessed lighting trim retention attachment system of claim 4, wherein the cross-member includes a slot, and the torsion spring legs are deformed against the bias to pass through and slidably engage the slot.

8. The recessed lighting trim retention attachment system of claim 1, wherein the distal end of the friction blade includes a hooked end.

9. The recessed lighting trim retention attachment system of claim 1, wherein the friction blade in its un-deformed state includes a vertical segment leading to an angled downward section leading to an upward hooked scraper.

10. A recessed lighting trim retention attachment system for supporting a light fixture trim inside a can, comprising:

at least two friction blade trim attachments, each attachment including:
an L-shaped bracket including a vertical portion;
a friction blade including a resilient cantilevered arm terminating in a scraper at a distal end;
a resilient member including a hump disposed proximate the L-bracket;
a cross-member joined to the friction blade such that the L-shaped bracket is slidably held therebetween along the vertical portion, wherein the resilient member slidably engages the cross-member such that the cross-member is biased in a direction along the vertical portion of the L-bracket;

13

wherein at least one of the cross-member and a finger in the L-bracket slidably engages the hump in the resilient member; and

wherein the L-bracket of each friction blade trim attachment is affixed to the light fixture trim, and the scraper frictionally engages the inside of the can to hold the light fixture trim inside the can.

11. The recessed lighting trim retention attachment system of claim **10**, wherein the resilient member includes a flat bar spring having a hump. 10

12. The recessed lighting trim retention attachment system of claim **10**, wherein the hump is resilient and deformable.

13. The recessed lighting trim retention attachment system of claim **10**, wherein the friction blade includes two opposed cantilevered arms terminating in a scraper at each distal end. 15

14. The recessed lighting trim retention attachment system of claim **10**, wherein the at least two friction blade trim attachments are interconnected by a center bracket that mounts to the light fixture trim. 20

15. A recessed lighting trim retention attachment system for supporting a light fixture trim inside a can, the trim retention attachment comprising: 25

14

an L-shaped bracket including a vertical portion; a friction blade having at least one resilient cantilevered arm terminating in a scraper at a distal end, wherein the cantilevered arm extends away from the vertical portion of the L-shaped bracket;

a resilient member disposed on the vertical portion of the L-shaped bracket;

a cross-member engaging the friction blade such that the L-shaped bracket is slidably held therebetween along the vertical portion, and the resilient member slidably engages the cross-member such that the cross-member is biased in a direction along the vertical portion of the L-bracket; and

wherein the L-bracket is affixed to the light fixture trim, and the scraper frictionally engages the inside of the can to hold the light fixture trim inside the can. 15

16. The recessed lighting trim retention attachment system of claim **15**, wherein the resilient member includes a hump that is integrated into the friction blade, which hump slidably engages a detent formed in the vertical portion of the L-shaped bracket.

17. The recessed lighting trim retention attachment system of claim **15**, wherein the resilient member includes a coiled torsion spring with legs that are biased apart, which legs are compressed against the bias to pass through and slidably engage a slot formed in the cross-member. 20
